INVENTOR.

UNITED STATES PATENT OFFICE.

CHARLES F. IRONS, OF PROVIDENCE, RHODE ISLAND.

DESIGN FOR A BADGE.

SPECIFICATION forming part of Design No. 20,645, dated March 31, 1891.

Application filed February 2, 1891. Serial No. 379,920. Term of patent 14 years.

To all whom it may concern:

Be it known that I, CHARLES F. IRONS, of the city and county of Providence, in the State of Rhode Island, have invented and produced 5 a new and original Design for a Badge Pin or Button, of which the following is a specification, reference being had to the accompanying drawing, forming part thereof.

The design consists of an annular band of 10 flat surface lying between two concentric circles. On the upper portion is a shield represented as overlying the annular band and having its lower point slightly projecting over the inner of said circles. Above the shield is an 15 ornamental ring large enough to receive a link, by which it is connected with a branch of a tree covered with thick foliage. This branch is slightly curved with its ends downward and its length is slightly greater than 20 the diameter of the larger of said circles. The link extends from the middle of the lower edge of the branch. Within the inner circle of the band and below the shield is an open space, which is circular, except where occupied 25 by the following details of the design. A right hand extending from a cuff and sleeve

is displayed as projecting horizontally and radially into this open space from the right side of the annular band. It is a closed hand, and between the thumb and forefinger is an 30 oblong square representing an addressed letter-envelope, which extends downward at an angle of about forty-five degrees, and its outer corners touch the inner circle. On the envelope are marks suggestive of an address 35 and postage-stamp.

The essential features of my design are the annular band, the shield, the central open space, and the hand and letter-envelope extending into said space.

What I claim is—

The design for a badge herein described, consisting of the representation of a leafy branch having a link from which depends a ring, a shield, and an annular band, the latter having a central open space into which extend a hand and a letter-envelope displayed, substantially as set forth.

CHARLES F. IRONS.
